UNITED STATES PATENT OFFICE.

WILLIAM HEYER, OF NEW YORK, N. Y.

PILING DEVICE FOR NAPKIN-FOLDING MACHINES.

1,210,168.

Specification of Letters Patent. Patented Dec. 26, 1916.

Original application filed August 6, 1915, Serial No. 43,984. Divided and this application filed December 18, 1915. Serial No. 67,572.

To all whom it may concern:

Be it known that I, WILLIAM HEYER, a citizen of the United States, and a resident of the city of New York, borough of Manhattan, in the county and State of New York, have invented a new and Improved Piling Device for Napkin-Folding Machines, of which the following is a full, clear, and exact description.

10 This invention relates to a piling device for napkin-folding machines, but it is not necessarily limited to this use, and this application is a division of an application for Letters Patent, Serial Number 43984, filed 15 by me August 6th, 1915, for improvements in napkin folding machines.

20 The invention has for its general objects to provide an improved mechanism for piling up articles successively fed thereto, in an efficient and expeditious manner.

25 A more specific object is the provision of a piling device including a novel arrangement of coacting grid-like elements, one of which is movable in a plane parallel with the articles to be piled, whereby an article delivered by a conveyer upon such element will be engaged by a descending grid-like element to hold the article while the first-mentioned element is withdrawn from under 30 the engaged article, and when fully withdrawn the second-mentioned grid-like element by its descending movement moves the article downwardly or out of the plane of the returning first-mentioned element, so 35 that the latter will hold the pile of articles down while the second-mentioned element moves backwardly to make way for the next article to be placed on the pile, the articles being supported on a yielding follower mov- 40 able step by step as the pile of articles increases.

45 With such objects in view and others which will appear as the description proceeds, the invention comprises various novel features of construction and arrangement of parts which will be set forth with particularity in the following description and claims appended hereto.

50 In the accompanying drawings, which illustrate one embodiment of the invention and wherein similar characters of reference indicate corresponding parts in all the views, Figure 1 is a sectional view of the piling apparatus taken on the line 1—1, Fig. 55 2; Fig. 2 is a vertical section taken on the

line 2—2, Fig. 1; Fig. 3 is a horizontal section on the line 3—3 Fig. 1; Figs. 4 to 7 inclusive are detail sectional views showing the various steps taken by the parts in the placing of an article on the pile; Fig. 8 is 60 a perspective view of the horizontally movable grid element; Fig. 9 is a perspective view of the pile supporting follower; Fig. 10 is a perspective view of the stop against which the articles strike in being delivered 65 into the piling mechanism.

Referring to the drawing, A designates the framework of a napkin folding machine which contains a pile-forming mechanism B to which folded napkins or other articles 70 a are delivered one by one by a suitably driven conveyer C.

The piling mechanism B comprises a plate-like follower 1 which is movable vertically on fixed guides 2, and the platform is 75 supported by front and rear flexible elements 3 and 4 connected with the corners, and these elements extend upwardly from the follower, the front elements passing over a guide roll 5, and all four elements winding 80 around a drum or roll 6. This roll 6 is rotated by means of cables or flexible elements 7 wound around the ends of the roll, and having their lower ends connected with helical extension springs 8 which yield as the 85 pile enlarges on the follower. Obviously any other suitable means may be employed for yieldingly supporting the follower.

When the follower is empty it occupies a position close to the conveyer C and lies 90 under a horizontally movable grid-like element 9 which has its side edges provided with guide grooves 10 for engaging the guide ribs 11 on the fixed bars 12 of the frame A. The element 9 comprises a plurality of parallel finger-like members 13 connected together by a transverse bar or back- 95 ing 14. This element 9 has the free ends of its members 13 pointing toward the conveyer C, and when the element 9 is in its rearmost position the beveled tips of the fingers 13 lie in close proximity to the discharge end c of the conveyer C, so that an article discharged by the conveyer will be 100 thrown upon the upper surface of the element 9. At the side of the piling device opposite from the conveyer C are upstanding stop members 15 rising from the bar 16 which is fastened to the frame A, and these fingers 15 extend between the fingers 110

13 of the element 9, and they stop the article discharged by the conveyer C in the right position, and they assist in holding the article in place while the element 9 is withdrawn from under the article. The grid element 9 is reciprocated by means of a rod 17 which is hingedly connected at 18 to the bar 14, and the rear end of the rod 17 is hingedly connected at 19 with a swinging arm 20 fulcrumed at 21, such arm having a member 22 which is wiped by a rotating cam 23 on the shaft 24, so that with each rotation of the shaft 24 the cam 23 will actuate the member 22, and this in turn swings the arm 20 to the right, Fig. 1, and causes the grid element 9 to move in the same direction. The grid element is returned from the position shown in Fig. 6 to that shown in Fig. 1 by a counterbalance weight or equivalent means 25 supported on an arm 26 connected with the shaft 21.

Coöperating with the grid element 9 is a depresser 27 in the form of a grid composed of U-shaped bars 28 having their ends connected with transverse bars 29 which are fastened to arms 30 that swing on a horizontal shaft 31. The members 28 of the swinging grid element 27 are so spaced as to enter between the members 13 of the horizontally movable grid element 9 so that the grid element 27 can move downwardly and engage the article and the element 9 and move such article downwardly below the plane of the element 9 when the latter is withdrawn, as shown in Figs. 6 and 7, and the grid element 27 remains in this position during the return movement of the grid element 9, the members 13 thereof moving between the members 28 of the upper grid element 27, as shown in Fig. 7. After the parts are in this position the upper grid element moves upwardly to the position shown in Fig. 1, so as to make way for the next article delivered by the conveyer C. The upper grid element is actuated by a swinging arm 32 fastened to a horizontal shaft 33 and connected by a link 34 to the upper grid element. On the shaft 33 is an arm 35 that is engaged by a rotary wiping cam 36 on the shaft 24, and also on the shaft 33 is an arm 37 which has a counterbalance weight 38, which weight raises the upper grid element while the cam 36 depresses the same. The cams 23 and 36 are so spaced with respect to each other that the grid elements 9 and 27 move in timed relation to each other and to the article-folding and delivering mechanism of the machine.

From the foregoing description taken in connection with the accompanying drawings, the advantages of the construction and method of operation will be readily understood by those skilled in the art to which the invention appertains, and while I have described the principle of operation, together

with the apparatus which I now consider to be the best embodiment thereof, I desire to have it understood that the apparatus shown is merely illustrative and that such changes may be made when desired as fall within the scope of the appended claims.

Having thus described my invention, I claim as new and desire to secure by Letters Patent:

1. A device of the class described comprising a yieldingly mounted vertically movable horizontal follower on which a pile of articles is adapted to be formed, a conveying means for horizontally supplying articles successively on the follower, a horizontal grid overlying the follower or pile thereon and arranged to receive an article from the conveyer, said grid and conveying means being disposed in meeting relation for permitting articles to pass directly to the grid from the conveying means, means for moving the grid parallel with the plane of the article thereon, means for holding the article from moving with the grid, and a device for engaging the article and moving the same out of the plane of the grid to permit the latter to return to its former position for receiving the next article.

2. A device of the class described comprising a yieldingly mounted vertically movable horizontal follower on which a pile of articles is adapted to be formed, a conveying means for horizontally supplying articles successively on the follower, a horizontal grid overlying the follower or pile thereon and arranged to receive an article from the conveyer, said grid and conveying means being disposed in meeting relation for permitting articles to pass directly to the grid from the conveying means, means for moving the grid parallel with the plane of the article thereon, means for holding the article from moving with the grid, a device for engaging the article and moving the same out of the plane of the grid to permit the latter to return to its former position for receiving the next article, and a device disposed at the side of the grid opposite from the follower and movable toward and from the follower and having members disposed parallel with and engageable between the members of the grid for pressing the pile of articles downwardly when the grid is withdrawn for permitting the grid to return to normal position and engage the top of the pile.

3. A pile-forming device comprising a horizontally movable element having a plurality of spaced finger-like bars, a conveyer located at the top side of the bars to deliver articles successively on the element, stationary means extending upwardly between the bars to form stops to arrest the articles delivered upon the element, a yielding follower at one side of the element, means for

reciprocating the element toward and from the conveyer, and a grid element movable toward and from the first-mentioned element to engage an article thereon and move such article and pile of articles on the follower, whereby the first-mentioned grid can return to a position over the top of the pile of articles, the free ends of the bars being arranged to meet the delivery end of the

conveyer for permitting articles to pass directly from the latter to the said bars. 10

In testimony whereof I have signed my name to this specification in the presence of two subscribing witnesses.

WILLIAM HEYER.
